7 Claims. (Cl. 18—17)

The present invention relates to a process and a machine for making galoshes, shoes with rubber soles and the like which are pressed in a presser with the use partly of an inner mould (last) dressed with caoutchouc and the required fabric lining partly of four or more side matrices moved towards the last, besides one or more sole matrices similarly moved towards the last and the invention is chiefly characterized by the fact that 5 the movement of the side matrices is so adjusted that the side matrices are moved rapidly towards the last, after which the said side matrices are moved only a short distance and slowly forward during the pressing and vulcanizing process 10 under which process the side matrices finally are kept stationary for a proportionate and adjustable period of time after which the side matrices are again moved outwards from the last.

The invention is further characterized in that 15 the sole matrix or sole matrices are moved in a way similar to the one in which the side matrices are moved.

After the actual pressing process the side matrices as well as the sole matrices are again moved 20 outwards so that the finished galosh or rubber shoe fitting on the last may be removed together with the latter and a new last dressed with caoutchouc and fabric lining may be inserted in the machine to replace that which has been re- 25 moved.

The side matrices may in a known manner be moved towards the last in converging directions. The movement of the side matrices normally 30 takes place in a plane at right angles to the direction of movement of the sole matrix or sole 35 matrices.

Another characterizing and peculiar feature of the invention consists in the slow movement of the sole matrix (if desired also of the side matrices) being brought about, during the actual 40 pressing process, by means of air pressure actuating the said matrix from an air chamber through the medium of a fluid string enclosed in a known manner in a pipe line, one end of which is connected with the said air chamber and the other end of which is connected with a pressure chamber connected direct or indirect with the matrix concerned.

Normally the machine or apparatus is constructed in the form of a kind of press having a horizontal table, on which the inner mould or last may be placed with the sole side turned upwards. Before the last is introduced in the machine it is covered or dressed with the necessary 50 layer of caoutchouc and linen lining or the like.

The horizontal press table of the machine is provided with the required guiding devices for the side matrices which have reciprocating movements in horizontal directions, so that they are caused to slide inwards when the machine is started and to become assembled around the inner mould or last. The sole matrix is arranged above the inner mould or last and has a vertical movement.

The slow movement of the side matrices during the actual process of pressing, as well as the rapid movement of these matrices towards the last and their quick removal from the last after the process of pressing are normally obtained through the medium of suitable cams actuated from a crank shaft, the said cams being curved in such a manner that the reciprocating motion is rapid, while the forward movement of the side matrices during the actual process of pressing becomes very slow on account of the very small pitch or ascent of the cam edge. The said cams are preferably arranged and mounted in such a manner as to enable them to be easily replaced by other cams adapted to extend the period of pressing or for introducing a different slow movement.

The sole matrix is most frequently moved up and down by means of a beam actuated from a crank, one end of the said beam carrying the sole matrix and the other end forming the fulcrum of the beam. Normally this fulcrum is not an absolutely fixed point, but is formed by a pivot carried by a piston which is under the influence of the pressure from an air chamber, the said pressure acting indirect on the piston through a string of fluid. In this manner it is obtained that the sole matrix gets a slow pressing movement, of the nature of a retightening or reclamping movement.

In the constructional form of the machine described above the arrangement is such that the crank shaft serving to operate the side matrices and the sole matrix, or causing these matrices to be operated as the case may be, only has intermittent motion. The crank shaft performs approximately half a stroke or turn when the machine is started and while the matrices become assembled around the last. Thereupon the crank shaft stops its movement and remains stationary for a variable period of time, during which the vulcanization takes place. Finally 105 the crank shaft is automatically switched in or coupled again, so as to complete its working stroke or turn, thereby removing the matrices from their contact with the last.

All the matrices are heated, with the excep- 110

tion of the inner mould or last, so that the caoutchouc placed around the last will become vulcanized either in part or completely during the process of pressing. The heating of the matrices 5 is most frequently done by means of electric current.

The drawings show as an example a constructional form of a machine in accordance with the invention.

10 Figs. 1 and 2 show diagrammatically how the matrices are arranged around the inner mould or last, in a machine with four horizontally reciprocating side matrices and one vertically movable sole matrix, Fig. 1 showing the tool arrangement in front elevation and Fig. 2 showing the tool arrangement as seen from above,

Fig. 3 shows the machine in front elevation.

Fig. 4 the same in side view.

Fig. 5 shows the same as seen from behind and 20 with the parts mounted on the press table removed.

Fig. 6 shows the machine as seen from above.

Fig. 7 shows part of the constructional details shown in Fig. 5, on a larger scale, and

25 Fig. 8 shows, also on a larger scale, a side view of the parts shown in Fig. 7.

The machine consists of a bottom frame 1 which forms the support of a press table 2. Underneath the press table 2 are arranged a driving shaft 3, a crank shaft 4, a cam shaft 5 and an intermediate shaft 6 (Fig. 5). The driving shaft 3 is provided with a loose pulley 7 and a fast pulley 8, and also with a toothed wheel 9 (Figures 4 and 5) which meshes with a toothed wheel 10 on the intermediate shaft 6, another toothed wheel 11 on the said shaft 6 meshing with a toothed wheel 12 on the crank shaft 4. The other end of the crank shaft carries a toothed wheel 13 meshing with a toothed wheel 14 on the cam shaft 5. The cam shaft 5 is rotated half a turn for each full turn of the crank shaft 4.

On the press table are arranged guides 15 for the side matrices 16, together with an upright 45 17 in the front end of which the sole matrix 18 is guidably mounted, by the sole matrix 18 being rotatably connected, by means of a pivot 56, with the front end of a beam 19. The centre of the said beam 19 is connected with the connecting rod 22 through the medium of a pivot 58 and link pieces 20 and 21, the connecting rod 22 performing a reciprocating movement up and down, driven from the crank shaft 4. The other end of the beam 19 is rotatably connected by 55 means of a pivot 57 with a piston 23 which surrounds a guide rod 24 so as to form a kind of hood or the like thereon.

The guide rod 24 is hollow, and the hollow space in the rod is connected with the inner 60 space of the piston 23 and also with an air chamber 25 supported by a hollow upright 26 mounted on the press table 2. The said hollow spaces in the piston 23, in the rod 24 and the upright 26 are filled with a fluid, so that the piston 23 is acted upon indirectly by the pressure of the air in the tank 25 through the medium of a string of fluid.

When the crank shaft is rotated the sole matrix 18 will be made to move up and down by the connecting rod 22 and the beam 19.

The side matrices 16 are so arranged that they can move horizontally in the guides 15 on the press table 2, and the said matrices obtain their reciprocating movement by means of the above-mentioned cam shaft 5 (Figs. 3 and 4). As in-

dicated in Fig. 3 the front end of the cam shaft 5 is provided with a cam 27 in the form of a double-bitted axe, and also with a wheel-shaped disc 28, the hollow side of which faces the interior of the machine and whose inner edge is provided with a pair of projecting cams 29. The cam 27 and the said cams 29 serve to impart to the side matrices the desired reciprocating movement, the removal of the side matrices, that is, their movement away from the last, being assisted by a pair of counterweights 30. Two guides 31 project into the space between the cam 27 and the inner surface of the disc 28. The said guides 31 are mounted on the inner ends of two racks 32 (Fig. 3) capable of moving horizontally and surrounded by suitable guiding units 33 (Fig. 4). The racks 32 are linkably connected with the counterweights 30 in a suitable manner. As may be seen from Fig. 3, the teeth of the racks 32 mesh with two toothed wheels 34 mounted on vertical shafts 35, the upper ends of which project above the press table and enter the guides 15 (Fig. 3, 4 and 6). The shafts 35 also carry toothed wheels 36, partly meshing with corresponding racks 37 on the front side matrices 16, and partly meshing with other toothed wheels 38 carried by vertical shafts 39 mounted or arranged inside the guides 15 (Fig. 6). The toothed wheels 38 mesh with corresponding racks 39 provided on the back side matrices 16 (Fig. 2).

The hindmost side matrices 16 (Fig. 2) need not necessarily be operated indirect from the toothed wheels 36 operating the foremost side matrices. The hindmost side matrices may, in the same way as the foremost side matrices 16, be driven direct from another rack provided in the back edge of the racks 32, the row of teeth on the front side of the racks 32 (Fig. 3) thus serving to operate the foremost side matrices, while the row of teeth on the back side of the racks 32 serve to operate the hindmost side matrices.

When the cam shaft is rotated it will operate, by means of the intermediate links and connections described above, the side matrices either towards the inner mould or last so as to surround and enclose the last, or away from the last.

The cam 27 causing the side matrices 16 to be moved inwards towards the last 40 is essentially formed as a double-bitted axe, as will be seen from Fig. 3. The portions of the cam curve drawn as circles in Fig. 3 are not strictly circles, however, but has a slow pitch, whereby it is obtained that the side matrices, after having been moved rapidly towards the last so as to surround the same, will be forced slightly closer together around the layer of caoutchouc covering the last, which movement will be effected extremely slowly, on account of the said slight pitch of the curve cam. This lastly described action constitutes the actual process of pressing as performed by the side matrices. The cams 27 may be replaced by other cams with a different pitch.

Under the machine table and close to the floor line a foot lever is arranged, not shown in the drawings, which by means of a suitable link mechanism serves to actuate an essentially crescent-shaped member 41 (Figs. 5, 7 and 8) extending around the back end of the crank shaft 4. The arrangement is such that the member 41 is made to move downwards when the foot lever is depressed. A suitably dimensioned spring tries to move the said crescent-shaped member 41, and thus also the foot lever, upwards. The said member 41 is carried by a fixed frame plate 42, mounted inside the said member, the said frame plate be-

ing formed by the back side of the hindmost bearing for the crank shaft (Fig. 4). The member 41 is secured to the frame plate 42 by means of two bolt members 43 or the like projecting through 5 suitably arranged vertically extending holes 44 in the member 41, so that the said member 41 may move freely downwards, when the foot lever is depressed. Two stops 45 and 46 are provided on the member 41, intended to stop and secure 10 a pawl 47 projecting from a coupling arranged within the hub of the large toothed wheel 12. The coupling is arranged in known manner so that the toothed wheel may rotate freely on the shaft when the pawl 47 is not secured and kept at 15 rest by one of the stops 45 or 46, while the toothed wheel 12 is coupled up with the crank shaft as soon as the pawl 47 clears the said stops. The frame plate 42 (Fig. 7) carries a two-armed rotatable ratchet 48 whose one end may engage 20 with the upper edge of the crescent-shaped member 41, and whose other end is adapted to be actuated by one or two projections 49 provided on a cam 50 carried by a ratchet wheel 51 rotatably mounted on the frame plate 42. The said ratchet 25 wheel 51 is actuated by a pawl 52 rotatably connected with a double lever 53 mounted on the frame plate 42. The lower end of the lever 53 is adapted to be acted upon by a number of projections 54 provided on a cam 154 rotating together with the toothed wheel 12. The upper end of the crescent-shaped member 41 is provided 30 with a projecting member 55 which, as may be seen in Fig. 7, is mounted adjacent to and directly below the pawl 52, in such a manner that 35 the projecting member 55 will lift the pawl 52 upwards when the member 41 is moved upwards, by the ratchet 48 being rotated, so that the said crescent shaped member 41 becomes disengaged and is brought under the influence of the foot lever 40 spring.

The devices above described and set forth, and thus also the whole apparatus now act and are operated in the following manner:—

When the inner mould or last 40—covered or 45 dressed with caoutchouc and linen lining or the like—has been placed in its proper position on the press table 2 the foot lever is depressed, which causes the press to start operations, the depression of the foot lever causing the crescent-shaped member 41 to be lowered (Fig. 7). By 50 this movement the pawl 47 becomes clear of the stop 45, the toothed wheel 12 being thereby coupled up with the crank shaft 4. This coupling action causes the crank shaft to be operated 55 from the driving shaft 3 (Fig. 4), and the crank shaft will rotate approximately half a turn, disengagement being effected again as soon as the pawl 47 strikes the stop 46. The said movement of the crank shaft will cause, in part, 60 that the beam 19 is actuated so that the sole matrix is moved downwards and performs its pressing operation, in part also, that the cam shaft 5 is rotated so that the side matrices also are moved towards the last and perform their 65 pressing operations. The beam 19 will follow the downward movement of the crank 22, during this movement rotating on the pivot 57 in the piston or cover 23. This rotation of the beam on the said pivot as a fixed fulcrum will only be 70 continued, however, until the sole matrix meets the great resistance offered by the layer of caoutchouc surrounding the last 40. From this moment the pivot 56 (Fig. 4) may practically speaking 75 temporarily be taken to constitute a fixed fulcrum, the continued movement of the crank

shaft in a direction downwards from now on forcing the pivot 57 and thus also the cover 23, which is in the form of a piston, downwards against the pressure from the air chamber 25. During that period in which the crank 22 is kept at 80 rest by the pawl 47 engaging the stop 46, the pivot 58 may temporarily be taken to constitute a fixed fulcrum, thus causing the beam 19 to be subjected to a slight rotating movement (anti-clockwise in Fig. 4). This rotating movement is 85 caused by the pressure in the air chamber, and the result hereof is that the sole matrix obtains a very slow and yielding movement downwards during that period in which the finishing pressing and vulcanization is done. 90

If desired the air pressure device may be omitted, so that the beam 19 (Fig. 4) is rotated on the pivot 57, which in this case acts as a fixed fulcrum and is adapted as such. As the beam is actuated from the crank 22, the sole matrix is 95 moved rapidly towards the last, after which the movement is slowed down while the crank approaches its dead centre position. The movement will be of the opposite nature during the subsequent movement of the crank away from the 100 lower dead centre position.

Along with the toothed wheel 12 a cam 154 rotates, whose projections 54 one by one will strike the lever 53. The pawl 52 is thereby brought into a horizontal reciprocating movement. The pawl 105 52, in its turn, will cause the ratchet wheel 51 to move, which wheel 51 during its rotation carries the cam 50 along with it. Sooner or later the projection 49 (or one of the projections 49 on the cam 50) will strike the projection on the 110 lower end of the ratchet 48, the upper end of this ratchet 48 being thereby moved out of engagement with the crescent-shaped member 41.

As soon as the crescent-shaped member 41 is 115 disengaged it will be moved upwards, whereby the pawl 47 clears the stop 46. When this occurs the crank shaft will again rotate about half a turn, until the crank shaft is again disengaged from the toothed wheel 12 when the pawl 47 strikes the stop 45. This rotation of the crank 120 shaft will cause, in part that the beam 19 is made to move so that the sole matrix is moved upwards and away from the last, and in part that the cam shaft 5 is also made to rotate so that the side matrices similarly are moved away from 125 the last.

The length of that period, during which the matrices enclose or surround the caoutchouc on the last, or, in other words, the duration of the combined pressing and vulcanizing period, 130 may be varied in part by causing the pawl 52 to move one, two or more teeth at each stroke on the ratchet wheel 51, and in part by making use of one, two or more projections 49 on the cam 50. Thus the use of two projections 49 instead 135 of a single projection only will cause the duration of pressing to be halved.

The easiest way of heating the matrices is to do this by means of an electric current, but there is nothing to prevent the heating being done in 140 any other way. The machine above described and explained is provided with a single sole matrix and four side matrices, but the machine may just as well be built with a sole matrix consisting of two or more single matrices. Similarly, there is nothing to prevent the machine being built with more than four side matrices. The machine may also be so constructed that the re-tightening or reclamping of the sole matrix, as mentioned and explained above, is not 145 150

done by the use of hydraulic means, but by means of the use of a cam with a small pitch, exactly similar to what has been described in respect of the side matrices. The re-tightening or re-clamping of the side matrices may just as well be done by the use of hydraulic force, instead of by using cams whose curved portions have a very small pitch. On the whole the constructional details of the machine described above may be varied to a considerable extent, without thereby departing from the principles of the invention.

I claim:

1. Apparatus for the manufacture of rubber footwear including an inner mold, a sole matrix and a plurality of side matrices characterized by a toothed wheel running loose on a crank shaft with which the toothed wheel is coupled or uncoupled by means of a coupling device comprising a pawl projecting beyond the said shaft, the said crank shaft actuating the sole matrix by means of a connecting rod linkably connected in a suitable manner with a rotatably mounted beam carrying the sole matrix, the said crank shaft simultaneously actuating the side matrices through the medium of a cam shaft whose cams actuate racks meshing with a toothed wheel serving to actuate the side matrices.

2. Apparatus for the manufacture of rubber footwear including an inner mold, a sole matrix and a plurality of side matrices characterized by a crescent-shaped member actuated by a foot lever, the said member being provided with, on the one hand, two stops and cooperating at the upper and lower position of the said member with a coupling device, which couples or uncouples the driving shaft of the machine with the driving member for causing them to rotate, and, on the other hand, a projecting member which, at the upper position of the crescent-shaped member raises a pawl, thus disengaging this pawl from a ratchet wheel, while the projecting member when the crescent-shaped member occupies its lower position, permits the pawl to actuate the ratchet wheel so that this movement of the said ratchet wheel will continue as long as the crescent-shaped member is in its lowermost position.

3. Apparatus for the manufacture of rubber footwear including an inner mold, a sole matrix and side matrices characterized by a toothed wheel running loose on the crank shaft of the machine which toothed wheel is coupled with uncoupled from the said shaft by means of a coupling pawl, the said toothed wheel being fixedly connected with a cam which cam by means of a lever actuates a pawl caused to engage or disengage the ratchet wheel through the action of a projecting member, the said ratchet wheel being fixedly connected with a cam provided with one or more projections serving to actuate a ratchet engaging the upper edge of the crescent-shaped member when the latter is lowered by the machine foot lever being depressed, the said ratchet tripping the crescent-shaped member, when acted upon by one of the said projections, the said crescent-shaped member being thereby disengaged and being permitted to be lifted under the action of a spring.

4. An apparatus for the manufacture of rubber

footwear and the like including a last mold on which the material is placed, a sole matrix to form the material on the sole of the galosh under pressing contact between such sole matrix and the mold, and a plurality of side matrices to exert a pressing contact on the sides of the material, said apparatus including a driven crank shaft for initially operating the sole matrix toward and in substantial contact with the material on the mold, fluid pressure means for operating the sole matrix for the pressing operation, means for feeding the side matrices toward the mold with a rapid constant motion and means for thereafter feeding the side matrices into and maintaining them in pressing contact with the material on the mold to a retarded movement limited as to distance.

5. In an apparatus for the manufacture of rubber footwear, a mold last on which the material is placed, a sole matrix operated to press the material on the last, a plurality of side matrices for forming the side material on the last, means for operating the sole matrix with respect to the last, and means for operating the side matrices with respect to the last, said means including cams formed in part to induce a rapid movement of the side matrices and in part to induce a materially slower movement of said side matrices, the cams transferring the respective movements unchanged to the side molds.

6. An apparatus for the manufacture of rubber footwear comprising an inner mold portion, a sole mold and side molds and characterized by a toothed wheel running freely on the crank shaft of the machine and coupled to and disengaged from the said shaft by a coupling pawl, the said toothed wheel being operatively connected with means which, during the rotation of the toothed wheel, move a pawl caused to work on or leave a ratchet wheel by means of a projecting member, the said ratchet wheel effecting motion of means which, after a predetermined interval of time corresponding to a predetermined angular rotation of the ratchet wheel, serve to move a locking device keeping temporarily a crescent-shaped member in its lowermost position, the said locking device releasing the crescent-shaped member for upward motion when the locking device is effected because the ratchet wheel has carried out the angular motion corresponding to the predetermined interval of time.

7. An apparatus for the manufacture of rubber footwear comprising an inner mold portion, a sole mold, side molds, a crank shaft, a toothed wheel running freely on the crank shaft, a pawl for coupling the wheel and shaft, a ratchet wheel, means operated by the toothed wheel to selectively operate the ratchet wheel, a crescent-shaped member, a locking device for holding said crescent-shaped member in its lowermost position, means operated by the ratchet wheel for releasing said lock following a predetermined angular rotation of the ratchet wheel, and means carried by the crescent-shaped member and operative in each position thereof for controlling the relation of the toothed wheel and crank shaft.

HENRY ARNOLD SKOV.
